[57] CLAIM

The ornamental design for a hair spray face shield, as shown.

DESCRIPTION

FIG. 1 is a front perspective view of a hair spray face shield in an unassembled condition, showing my new design;

FIG. 2 is a rear perspective view thereof;

FIG. 3 is a top front perspective view, shown in the assembled condition;

FIG. 4 is a bottom, rear perspective view thereof;
FIG. 5 is a plan view, shown in the unassembled condition;

FIG. 6 is a front end elevational view, in the assembled condition; and

FIG. 7 is a rear end elevational view thereof.
